(57) **CLAIM**

The ornamental design for a floodlight, as shown and described.

DESCRIPTION

FIG. 1 is a front perspective view of the floodlight, according to a first embodiment, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof.

FIG. 9 is a front perspective view of the floodlight, according to a second embodiment, showing our new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines are used in the drawings to illustrate features of the floodlight that form no part of the claimed design.

1 Claim, 12 Drawing Sheets
